UNITED STATES PATENT OFFICE.

ISAAC MITCHELL, OF WOODBINE, IOWA.

CAR-CO尤LING.

SPECIFICATION forming part of Letters Patent No. 349,400, dated September 21, 1886.

Application filed June 26, 1886. Serial No. 206,348. (No model.)

To all whom it may concern:

Be it known that I, ISAAC MITCHELL, a citizen of the United States, residing at Woodbine, in the county of Harrison and State of Iowa, 5 have invented a new and useful Improvement in Car-Couplings, of which the following is a specification.

My invention relates to an improvement in car-couplings; and it consists in the peculiar 10 construction and combination of devices, that will be more fully set forth hereinafter, and particularly pointed out in the claim.

In the drawings, Figure 1 is a side elevation of a car-coupling embodying my improvements. Fig. 2 is a vertical longitudinal sectional view of the same. Fig. 3 is a top plan view. Fig. 4 is a detached plan view of the keeper for the operating-rod.

A represents the draw-head, which is provided with the enlarged outwardly-flared mouth B to receive the coupling-link. Through the center of the draw-head, in rear of the mouth, is made a vertical longitudinal slot, C. The upper side of the draw-head, near the mouth, is thickened, as at D, and through the said draw-head, near the mouth and in front of the slot C, is a vertical transverse slot, E.

F represents an arm, the lower portion of which is in the slot C. The lower end of this 30 arm is pivoted to the under side of the draw-head by means of a transverse pin, G, which is journaled in keepers H, that are secured to the under side of the draw-head. From the upper end of the arm F, on the front side 35 thereof, projects a stud, f.

I represents a coupling-pin, which fits in the slot E, and is provided near its center with a transverse horizontal opening, K. On the rear side of the coupling-pin is a vertical groove, 40 L, which extends from the opening K nearly to the top of the coupling-pin.

M represents a spring, which is secured in the upper rear side of the slot C and bears against the rear side of the pivoted arm F, so 45 as to move the upper end of the latter forwardly and cause the stud f of the said arm to engage the groove L on the rear side of the coupling-pin.

N represents the usual coupling-link, which 50 is adapted to enter the draw-head.

When the coupling-pin is raised to the

position shown in Fig. 2, the stud f engages the opening K, and thus supports the coupling-pin in its elevated position. When the cars come together, the coupling-link enters 55 the draw-head and strikes against the front side of the pivoted arm F, and forces the said arm rearwardly against the tension of the spring M, thus causing the stud f to disengage the opening K and release the coupling-pin, 60 which then drops by its own gravity and passes through the link, thus coupling the cars together automatically.

In order to raise the coupling-pin from the top of a freight-car, I provide a vertical rod, 65 O, which is provided near its upper end on one side with a feather or spline, P, which passes through a keeper, R, that is secured on the end of the car. The said keeper is provided with a slot, S, through which the spline and the 70 main portion of the rod pass, and the rod is provided at the upper end of the spline with an enlarged collar, O', and slightly below the lower end of the spline with a similar collar, O'. The lower end of the rod is attached to 75 the upper end of the coupling-pin by means of a chain, T.

If it be desired to permit two cars to come together without coupling, the rod O is drawn upwardly, so as to raise the coupling-pin, and 80 the said rod is then partly turned, so as to cause the spline to pass out of line with the slot S and bear upon the upper side of the keeper R. This supports the rod O, and therefore the coupling-pin, in an elevated position, so that 85 when the cars come together the coupling-link strikes against the pivoted arm and disengages the latter from the coupling-pin; but as the said pin is supported in its elevated position by the rod O, it will be seen that the pin will 90 not descend in the draw-head, and consequently the cars will not become coupled together.

A car-coupling thus constructed is cheap and simple, is strong and durable, is automatic in operation, and prevents the necessity 95 of going between the cars in order to operate them, and thus endanger life and limb.

Having thus described my invention, I claim—

The combination of the draw-head having 100 the vertical slot C and the vertical opening E, the arm F, having its lower end pivoted in

the slot *e*, and provided with the stud *f* at its upper end, the spring *M*, bearing against the rear side of the arm, and the coupling-pin having the opening *K* near its center to engage 5 the stud *f*, and the groove *L*, extending vertically from the opening *K*, substantially as described.

In testimony that I claim the foregoing as my own I have hereto affixed my signature in presence of two witnesses.

ISAAC MITCHELL.
